(57) **CLAIM**

The ornamental design for a camera, as shown and described.

DESCRIPTION

FIG. 1 is front elevational view thereof;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, right, and top perspective view thereof; and,

FIG. 8 is an enlarged view of a portion of FIG. 1 from line 8.-8. of FIG. 1.

The broken lines in the drawings show unclaimed features of the camera and form no part of the claimed design.
